UNITED STATES PATENT OFFICE

2,572,381

FLUSH TYPE SLIDING HINGE

Chester A. Peterson, Vancouver, Wash.

Application May 13, 1947, Serial No. 747,652

2 Claims. (Cl. 312—323)

1

This invention relates to hinges and more particularly to a sliding hinge.

It is an object of this invention to provide an improved hinge of the kind to be more particularly described hereinafter for mounting radios or other such devices in a closed compartment in such a manner that the frame of the radio is hingedly connected to the cabinet or compartment whereby the frame or base may be inverted about the hinge for working on the wiring of the radio usually located on the under side of the frame or base. The hinge is so located that it will be concealed within the cabinet or compartment in the closed position of the radio and may slide outwardly to permit rocking the frame to the inverted position in the open position of the radio without removing it entirely from the cabinet or compartment. This type of hinge is particularly adaptable to a radio as installed in automobiles, as police, scout, cars and others where the radios must be maintained in perfect condition.

Another object of this invention is to provide a hinge of this kind whereby a frame or base may be slidably and rockably mounted as in a cabinet and so constructed and arranged that the base may be bodily removed from attachment to the cabinet by merely raising the base from the hinge.

Still another object of this invention is to provide a hinge of this kind for mounting a radio base or the like in a container whereby the radio may be readily removed for working on the underneath wiring. A similar hinge or hook may be mounted on a bench in a shop so the radio when removed from the cabinet may be supported on a similar hinge in the shop by merely engaging the lugs or pintle in the hooks, where it may be worked on freely.

A further object of this invention is to provide a hinge of this kind for removably supporting a radio base in a cabinet or compartment in such a manner that the base may be slidably and rockably mounted on the cabinet in such a manner that it is firmly supported in its open position and held from dropping off the hinge and will permit the free access to the wiring below the base.

A still further object of this invention is to provide a hinge of this kind particularly distinguished by its safety features. That is, when a radio or other device is pulled out of the cabinet, so that it may be worked on, or placed in a working position, there is no possibility of the apparatus coming unhooked or dropping off the hinge support. The instrument can only be removed by raising it to an upright position.

With the above and other objects in view, my invention consists in the arrangement, combina-

tion and details of construction disclosed in the drawings and specification, and then more particularly pointed out in the appended claims.

In the drawings,

5 Figure 1 is a front elevation of a radio cabinet or the like constructed with the front side thereof mounted on a hinge constructed according to an embodiment of this invention.

10 Figure 2 is a longitudinal section taken on the line 2—2 of Figure 1, showing the chassis in extended position in dotted lines.

Figure 3 is a horizontal section taken on the line 3—3 of Figure 1.

15 Figure 4 is a fragmentary longitudinal section, partly broken away, taken on the line 4—4 of Figure 3.

Figure 5 is a fragmentary detail side elevation of the hinge in the extended position.

20 Figure 6 is a fragmentary section taken on the line 6—6 of Figure 5.

Figure 7 is a longitudinal section taken on the line 7—7 of Figure 4.

25 Referring to the drawings, the numeral 10 designates generally the cabinet for a radio or the like, as more particularly designed for supporting a radio in an automobile. The cabinet 10 is provided with a hinged front wall 11 for removing the chassis or base of the radio when it is necessary to perform work on the wiring or other maintenance.

30 While the front wall 11 is hingedly connected to the cabinet 10, hinged or rocking movement of the front wall is usually insufficient to rock the radio base or chassis to a position suitable for working on the wiring which is disposed on the lower side of the base. For working on this wiring it is usually most convenient to dispose the radio in as near to an inverted position as possible. By using a hinge of the kind to be more 35 specifically described hereinafter, the front wall 11 and radio chassis 12 may be rocked from the cabinet 10 to an inverted position slightly forward of the front edge of the cabinet. The front wall 11 is usually provided with openings as 14 and 15 through which the control knobs and the speaker of the radio are adapted to extend. By mounting the radio in this manner the control knobs and other obstructions which are disposed on the forward side of the front wall 11 need not 40 be removed for removing the chassis from the cabinet.

45 The supporting means 16 by which the front wall 11 and radio chassis 12 are mounted in the cabinet 10 includes an elongated plate 17 which is adapted to be fixed to the inside of the opposite side walls of the cabinet 10 by bolts 18 or other suitable fastening devices. The plate 17 is disposed rearwardly of the front edge of the cabinet 10 and front wall 11. The plate 17 is formed 50 with a longitudinally extending groove 19 on one

side thereof to provide a guide or channel between the plate 17 and the wall of the cabinet.

The groove 19 extends throughout the length of the plate 17 opening at each end. The plate 17 is further formed with an elongated slot 20 near the rear end thereof, the slot 20 opening through the plate to communicate with the groove 19. As shown in Figure 4, the slot 20 opens rearwardly of the plate 17, together with the groove 19. An elongated supporting bar or arm 21 is slidably engaged in the groove 19, the bar 21 being substantially the same length as the plate 17. The arm 21 is held in place by being disposed between the plate 17 and the wall of the cabinet in the groove 19.

For limiting the sliding movement of the arm 21, a stop pin 22 is fixed on the arm near the rear end thereof. An upwardly directed bill 24 is fixed to or formed on the forward end of the arm 21. The bill 24 is formed with a downwardly extending arm or shank 25 and a forwardly and upwardly extending hook forming arm 26. The bill 24 is bent inwardly along the length of the shank 25 as at 27, to provide clearance for the attaching bolt 28 which engages in the hook 26. A pin or pivot 28 is fixed to the base or chassis 12 of the radio at a point rearwardly of the front wall 11 a distance substantially equal to the width of shank 25 and spaced above the bottom extremity of the chassis a distance substantially equal to the length of said shank 25. The pivot pin 28 is formed with a threaded shank 30, engaging through the base 12, with which a nut as 31 is engaged for fixing the pin 28 thereto. The pin 28 is further formed with an enlarged annular head 29 spaced outwardly from the wall of the base 12. As the pin 28 is engaged in the hook 26, the hook is disposed between the head 29 and the base 12 to hold the base against lateral movement in the hinges.

In the use and operation of this hinge 16 when the radio is completely assembled and installed the pin 28 is engaged in the bill 24 and the arm 21 is retracted into the plate 17, as shown in Figures 2 and 4. For rocking the chassis of the radio to an inverted position, the front wall 11 is pulled forwardly so the arm 21 slides forwardly in the plate 17 until the pin 22 engages the extreme forward end of the slot 20. The base or chassis 12 may then be pivoted about the pin 28 in the bill 24 to an inverted position as shown in dotted lines in Figure 2, whereupon the rear surface of the front plate 11 will engage the vertical back edge of the elongated shank 25 and the under edge of arm 21. The spacing of each pin 28 relative to wall 11 is arranged to allow for rotation of the chassis substantially 180 degrees about the axis of said pins so as to provide for inverted positioning of the chassis with the under side faced upwardly in full view of a repairman and ready of access thereto. Certain types of wiring of radios of this kind connect the radio to the speaker and sources of power through slide plugs not shown in the drawings. The plugs will be disconnected upon sliding movement of the chassis forward from the cabinet 10.

At certain times it may be desirable to remove the entire radio chassis from the cabinet 10 and hinges 16. This may be readily accomplished by rocking the front wall 11 and chassis 12 partly about the pin 28 and lifting the entire assembly from the hooks. For supporting the radio thus removed on a bench in a shop similar hinges may be fixed on a suitable base so that the pins 28 may be engaged in hooks similar to the hooks 24

so that no other attaching means need be provided. When the radio is completely put back in condition it may be re-installed by merely engaging the pins 28 in the hooks, rocking the chassis 12 to the horizontal position and sliding the arms 21 back in the plate 17.

I do not mean to confine myself to the exact details of construction herein disclosed, but claim all variations falling within the purview of the appended claims.

What I claim is:

1. In a cabinet having an open front, of a pair of oppositely disposed longitudinally grooved guide members fixed on inner side walls of the cabinet, each of said guides being formed with a longitudinally extending slot communicating with the groove formed therein and having a closed end disposed from the open front, an elongated arm slidably carried by the groove of each guide member, a pin carried by each arm engaging in said slot of said guide, said arms having dependent ends formed at right angles and extendable relative to said guides, said dependent ends having forwardly extending and upwardly opening hooks, a base member slidable within the cabinet, said base member being formed with a vertical front wall extending laterally beyond the dependent ends, transverse pivot members carried by said base and engageable in said hooks, said vertical front being engageable with the rear edges of said right angled ends of the arms after withdrawal of said base from the cabinet and pivotal movement of 180 degrees for securely suspending said base from said hooks.

2. In a cabinet having an open front, of a pair of oppositely disposed longitudinally grooved guide members fixed on inner side walls of the cabinet, an elongated arm slidably carried by the groove of each guide member, said arms having dependent ends formed at right angles and extendable relative to said guides, said dependent ends having forwardly extending and upwardly opening hooks, a base member slidable within the cabinet, said base member being formed with a vertical front wall disposed forwardly of said dependent ends, oppositely disposed transverse pivot members carried by said base and engageable in said hooks, said transverse pivot members being disposed rearwardly of said front wall and upwardly from the bottom of said base member, said vertical front being engageable with the rear edges of said right angled ends of the arms after withdrawal of said base from the cabinet and pivotal movement of 180 degrees for suspending said base in an inverted position from said hooks.

CHESTER A. PETERSON.
